UNITED STATES PATENT OFFICE

HORACE EDWARD FARMER, OF DETROIT, MICHIGAN, ASSIGNOR TO KELSEY-HAYES WHEEL CORPORATION, OF DETROIT, MICHIGAN, A CORPORATION OF NEW YORK

MACHINE FOR FORMING HOLES IN ARTICLES

Application filed June 3, 1929. Serial No. 367,933.

The invention relates to machines for forming holes in articles and refers more particularly to machines for forming spoke holes in the hub members of vehicle wheels. One of the objects of the invention is to so construct a machine that it may be used to form spoke holes in a number of different hub members. Another object is to so construct the machine that it may be used to form different sets of spoke holes in the same hub member. A further object is to so mount the carrier for the hub member that the hub member may be moved into engagement with the die in position to be operated upon by the punch. With these as well as other objects in view, the invention resides in the novel features of construction and combinations and arrangements of parts as more fully hereinafter set forth.

In the drawings:—

Figure 1 is a side elevation, partly in section, of a machine embodying my invention;

Figure 2 is a plan view thereof;

Figure 3 is an end view thereof, partly in section;

Figure 4 is a cross section on the line 4—4 of Figure 1.

The machine has the base 1 and the ram 2 vertically reciprocable toward and away from the base. This ram has secured thereto the holder 3 in which is mounted the depending punch 4. The base has the upwardly extending guides 5 for the holder and has mounted thereon the die 6 for cooperating with the punch 4. The base has fixedly secured thereto the table 7 upon which is mounted the support for the work article, which latter in the present instance is the sheet metal hub member or shell 8 of a vehicle wire wheel.

The support for the hub shell comprises the lower base member 9 which is longitudinally slidable upon the table 7, the upper base member 10 which is slidable transversely upon the lower base member 9 and a pivotal mounting for the hub shell upon the upper base member 10. The lower base member 9 is adapted to be moved longitudinally by means of the plunger rod 11 connected thereto and to a plunger within the air cylinder 12, the latter being mounted

upon the table 7. For limiting the longitudinal movement of the lower base member inwardly, there is the set screw 13 secured to the inner end of this base member and engageable with the portion of the base 1 above the table 7. The upper base member 10 is adjustable transversely of the lower base member 9 by suitable means such as the threaded rod 14. This upper base member has the parallel upwardly extending arms or uprights 15 at the upper ends of which is mounted the pivotal mounting for the hub shell.

The pivotal mounting comprises the pivotal member 16 having the parallel arms inside and adjacent to the arms 15, the second pivotal member 17 inside the arms of the pivotal mounting 16 and the carrier 18 upon the second pivotal member. 19 are aligned pins journaled in the arms 15 of the upper base member 10 and extending into and fixedly secured to the pivotal member 17. The pivotal member 16 is journaled upon these pins. For securing the pivotal member 16 in its adjusted positions suitable means such as the bolts 20 and the nuts 21 are provided, the former extending through transverse holes in the arms 15 and arcuate slots in the arms of the pivotal member 16 and concentric with the axes of the pins 19. The carrier 18 has the base plate 22 from which extends transversely the pilot pins 23 for engaging the holes 24 in the hub shell. This carrier has fixedly secured to the base plate the indexing wheels 25 and 26 which are respectively used in approximately positioning and predeterminedly positioning the carrier.

For clamping the hub shell to the carrier, there is the plunger rod 27 which extends axially through the pivotal member 17 and through the carrier 18 and is secured at its rear end to a plunger within the air cylinder 28, which latter is fixedly mounted upon the pivotal member 17. 29 is a clamping plate engageable with the hub shell and adapted to encircle the plunger rod and 30 is a suitable washer engageable with the clamping plate and embracing the plunger rod and abutting a shoulder at the front end of the plunger rod, which in the present instance is formed

by the nut 31 threaded upon the plunger rod.

The pivotal member 17 is connected to the pivotal member 16 by means of the cam or eccentric 32. This cam has the main portion 33 journaled in the block 34 which is mounted in the guide 35 fixedly secured to the pivotal member 16. The block is slideable in a slot in the guide extending radially from 10 the pivot of the pivotal member 16. The cam has at the ends of its main portion the cranks 36 which are journaled in the arms 37 fixedly secured to the pivotal member 17. The cam has fixedly secured to one of its ends adjacent a crank 36 the arm 38 which is formed with the L-shaped slot 39. 40 is a slide having the pin 41 engaging in the L-shaped slot, the slide being reciprocably mounted in the guide 42 carried upon the pivotal member 17 20 and extending transversely of its axis. The arrangement is such that upon downward movement of the slide 40 its pin 41 engaging the arm 38 rotates the cam which, through its cranks 36 engaging the arms 37, causes the 25 pivotal member 17 supporting the hub shell carrier to swing downwardly to lower the part of the hub shell to be punched upon the die 6.

For indexing the hub shell carrier the slide 30 40 has pivotally mounted thereon the dog 43, the nose of which is normally held outward by means of the coil spring 44 to engage a notch of the indexing wheel 25 and rotates this indexing wheel in a counter clockwise 35 direction, as shown in Figure 4, a distance of one notch. This dog is mounted at the lower end of the slide in a position such that it will not engage its indexing wheel until the slide has moved upwardly far enough to 40 rotate the cam 32 to raise the hub shell from the die. The guide 42 carries dogs for engaging the notches of the indexing wheel 26, these notches being so formed that this indexing wheel is positively located and held 45 from rotation in either direction. In detail, 45 is a dog pivotally mounted upon the guide 42 and having a nose engageable in a notch of the indexing wheel 26 to prevent rotation of this indexing wheel in a clockwise direction, this dog however permitting rotation of the indexing wheel in a counter clockwise direction. 46 is a second dog pivotally mounted upon the guide 42 and having at one end the nose 47 for engaging a notch of the indexing wheel 26 to hold this indexing wheel 50 from rotation in a counter clockwise direction.

This dog has at its other end the shoulder 48 which is engageable by the spring pressed bolt 49 carried by the slide 40 to swing the nose 47 out of engagement with the indexing wheel 26. 50 is another dog in the nature of a bolt having a nose engageable with a notch of the indexing wheel 26 to hold the indexing wheel from rotation in either direc-

tion. This bolt extends transversely of the guide 42 and has mounted thereon and extending transversely thereof a roll 51, which latter extends within the cam slot 52 extending longitudinally in the slide 40. The bolt 49 is positioned relative to the shoulder 48 of the dog 46 and the cam slot 52 is so arranged relative to the roll 51 that the noses of both dogs 46 and 50 are withdrawn from the indexing wheel 26 prior to engagement of the nose of the dog 43 with the indexing wheel 25.

For reciprocating the slide 40, the ram 2 has secured thereto the arm 53 which is formed with the horizontally extending slot 54. This arm is adjustably secured to the ram as by means of the bolts 55 threaded into the ram and extending through transverse slots 56 in the foot flange of the arm. 57 is an upright rigidly secured to the upper base member 10 and having the longitudinally extending slot 58. 59 is a shoe extending through and slidably engaging in the slots 54 and 58, this shoe being connected to the nut 60 upon the threaded rod 61. As shown, the shoe is connected to the nut by means of the bolt 62 which provides for rotation of the nut relative to the shoe. The lower end of the threaded rod 61 is pivotally connected to one end of the bell crank 63, 65 which is pivotally mounted at 64 upon a lateral extension 65 of the pivotal member 17. The other end of this bell crank is provided with the longitudinally extending slot 66 for receiving the pin 67 upon and extending transversely of the slide 40.

With the arrangement as above described, the hub shell carrier may be adjusted horizontally in transverse directions and also vertically. This hub shell carrier may also be automatically lowered to engage the part of the hub shell to be punched with the die and may be automatically indexed when raised, these latter operations being dependent upon movement of the ram. By reason of this adjustable construction, the same machine may be used for forming different sets of holes in the hub shell. Also by substituting different forms of hub shell carriers different hub shells may be operated upon by the same machine.

What I claim as my invention is:

1. A machine having a tool for fashioning an article and a support for the work article having upper and lower base members movable transversely of each other in a horizontal direction, a pivotal member adjustably mounted upon said upper base member, a second pivotal member connected to said first mentioned pivotal member and adapted to be adjustable therewith, and a carrier for the work article mounted upon said second pivotal member to rotate transversely to the axis thereof.
2. A machine having a reciprocable punch,

a cooperating stationary die, a rotatable carrier for the work movable in a direction transverse to its axis of rotation to carry the work toward said die and also adjustable in transverse directions transverse to the first mentioned direction, and means for rotating said carrier and moving said carrier transversely to its axis of rotation in timed relation to the operation of said punch.

10 3. A machine having a tool for fashioning an article, a support for the work article having a base member adjustable in transverse directions, a pivotal member adjustably mounted upon said base member to swing in a direction transverse to the first mentioned directions, a carrier for the work article pivotally mounted upon said base member to swing in the same direction as said pivotal member, and means for swinging said carrier relative to said pivotal member, including a cam connecting said work carrier to said pivotal member.

4. A machine having a reciprocable punch, a cooperating stationary die, a support for the work article having a base member, a pivotal member adjustably mounted upon said base member, a second pivotal member adapted to swing parallel to said first mentioned pivotal member, a carrier for the work article journaled upon said second mentioned pivotal member and having an indexing wheel, a cam connecting said pivotal members to each other, and a common means for actuating said cam and indexing wheel in timed relation to move the work article into operative position relative to said die, to move the work article away from said die and during this latter movement to rotate said indexing wheel.

40 5. A machine having a base, a ram reciprocable toward and away from said base, a punch carried by said ram, a cooperating die mounted upon said base, a support for the work article having a base member mounted upon said base to move in one direction, a second base member mounted upon said first mentioned base member to move in a transverse direction, said second base member having an upright, a pivotal member mounted upon said upright and adjustably secured thereto, a second pivotal member mounted upon said upright, a carrier for the work article journaled upon said second pivotal member and having an indexing wheel, a cam connecting said pivotal members to each other and rotatable to swing said second pivotal member to engage the work article with or release the work article from said die, a reciprocable slide, means for operating said slide from said ram, and means upon said slide for actuating said cam and indexing wheel in timed relation.

6. A machine having a reciprocable punch, a cooperating stationary die, a rotatable carrier for the work movable in a direction

transverse to its axis of rotation to carry the work toward and away from the die, means operable in timed relation to the reciprocation of the punch for moving the carrier and work thereon away from the die, and means automatically operable in timed relation to the movement of the carrier away from the die to rotate the carrier.

7. A machine having a reciprocable punch, a cooperating stationary die, a rotatable carrier for the work movable in a direction transverse to its axis of rotation to carry the work toward and away from the die, means automatically controlled by the reciprocation of the punch for moving the carrier and work thereon away from the die, and means automatically operable in timed relation to the movement of the carrier away from the die for rotating the carrier an accurate predetermined amount to position another portion of the work in operative relation to the punch.

8. A machine having a reciprocable punch, a cooperating stationary die, a work carrier pivotally mounted intermediate the ends thereof upon a part of the machine for swinging movement toward and away from the die, means for rotating said carrier, means automatically operable in timed relation to the reciprocation of the punch for swinging the work carrier away from the die, and means operable in timed relation to said last-mentioned means for rotating the work carrier to position another portion of the work in operative relation to the punch.

9. A machine having a movable tool, a stationary member for positioning a work article while being fashioned by the tool, a rotatable work carrier for the work article movable in a direction transverse to its axis of rotation to carry the work article toward and away from the stationary member, means operable in dependence upon movement of the tool for automatically effecting movement of the work carrier toward and away from the stationary work positioning member, and means operable in timed relation to said last-mentioned means for rotating the work carrier.

10. A machine having a movable tool for fashioning an article, a stationary member for positioning the article during the fashioning operation, a rotatable work carrier for the article movable toward and away from the stationary positioning member, means operable in timed relation to the actuation of said tool for effecting movement of said carrier toward and away from the positioning member, and a support for the work carrier mounted for adjustment in directions transverse to each other.

11. A machine having a movable tool for fashioning an article, a stationary member for positioning the article during the fashioning operation, a rotatable carrier for
